US0D1008030S

(12) **United States Design Patent** (10) Patent No.: **US D1,008,030 S**
Gruzelier et al. (45) Date of Patent: ** Dec. 19, 2023

(54) **BOTTLE**

- (71) Applicant: **The Procter & Gamble Company**, Cincinnati, OH (US)
- (72) Inventors: **Julian Richard John Gruzelier**, Vaud (CH); **Gillian Meredith Anne Haro**, Amsterdam (NL); **Brett Tom**, Richmond, CA (US); **Wei Gu**, Singapore (SG); **Reid Andersen**, Schlegel, Brooklyn, NY (US); **Danvu Nam Nguyen**, San Francisco, CA (US); **Calvin Shenghuai Lin**, Singapore (SG); **Longfei Zhang**, Singapore (SG)
- (73) Assignee: **The Procter & Gamble Company**, Cincinnati, OH (US)
- (**) Term: **15 Years**
- (21) Appl. No.: **29/863,391**
- (22) Filed: **Dec. 19, 2022**

(57) **CLAIM**

The ornamental design for a bottle, as shown and described.

DESCRIPTION

FIG. 1 is a front perspective view of a bottle, embodying our new design;

FIG. 2 is a front view thereof;

FIG. 3 is a back view thereof;

FIG. 4 is a first side view thereof;

FIG. 5 is a second side view thereof;

FIG. 6 is a top view thereof; and,

FIG. 7 is a bottom view thereof.

The broken lines shown in the drawings depict portions of the bottle that form no part of the claimed design.
